AUTOMATIC WEIGHING MACHINE

Warren D. Jordan, Joliet, Ill., assignor to Franklin Steel Works, Joliet, Ill., a corporation of Illinois

Application July 9, 1934, Serial No. 734,302

11 Claims. (Cl. 249—66)

The invention relates to automatic filling and weighing machines and has reference more particularly to machines for filling containers with material in a powder or granular form.

5 An object of the invention is to provide a novel machine of the type described having a vertically movable platform for supporting the container and which is forced downwardly as the material is delivered to the container to cause actuation 10 of mechanism which will stop operation of the feeding means.

A further object of the invention is to provide 15 feeding augers of improved construction having simultaneous operation to deliver material to the container and which will otherwise operate in unison.

A further object of the invention is to provide 20 improved mechanism for delivering material to the container comprising main feeding augers for delivering the bulk of the material, and secondary feeding means for feeding a small stream or dribble, and which will operate after the bulk feeder has stopped to gradually bring the material in the container to the desired weight.

25 A further object is to provide trip mechanism directly responsive to the movements of the platform supporting the container for opening and closing an electric circuit to control operation of the feeding augers and which will be sensitive 30 and accurate in operation and of generally novel construction.

A further object is to provide mechanically actuated trip mechanism for opening and closing 35 an electric switch which will be protected against arcing to insure long life.

A further object resides in the provision of 40 duplicate trip mechanism for controlling the operation of the secondary feeding augers independently of the main augers and which can be adjusted to cause both feeding means to simultaneously deliver material at the start of the operation while permitting the secondary means to continue after the main feed has stopped to gradually bring the container to the proper weight.

45 A further object is to provide a weighing machine of the type described with novel structure for supporting the platform for vertical movement and which will have substantially frictionless joints making a sensitive weighing scale and one that will also stand up under severe conditions.

A further object is to provide supporting means 50 for securely mounting the augers for operation and which will make their removal a relatively easy task to facilitate cleaning and the like.

With these and various other objects in view, the invention may consist of certain novel features of construction and operation as will be more fully described and particularly pointed out in the specification, drawings and claims appended hereto. 5

In the drawings which illustrate an embodiment of the device and wherein like reference characters are used to designate like parts—

Figure 1 is an elevational view of a weighing 10 machine constructed in accordance with the present invention;

Figure 2 is a vertical sectional view taken 15 through the hopper and showing the drive for the feeding auger;

Figure 3 is an end view looking toward the left 20 of Figure 1;

Figure 4 is a transverse sectional view showing 25 the trip mechanism for causing actuation of the mercury switch;

Figure 5 is an elevational view of the trip mechanism of Figure 4;

Figure 6 is a detail sectional view of the holder 30 for the augers;

Figure 7 is an elevational view of the trip mechanism showing the modified tripping and resetting means;

Figure 8 is a vertical sectional view showing the 35 arrangement for driving the main feeding augers and auxiliary auger;

Figure 9 is a cross-sectional view taken on line 9—9 of Figure 8;

Figure 10 is a cross-sectional view taken on line 10—10 of Figure 8;

Figure 11 is an elevational view of the trip 35 mechanism and tripping means for the structure of Figure 8;

Figure 12 is an elevational view showing a modified design of scale beam and associated structure; and 40

Figure 13 is a transverse sectional view taken on line 13—13 of Figure 1 and showing the frictionless bearings for mounting the beam members.

In Figure 1 of the drawings the machine 45 selected for illustration is shown as comprising a suitable support 10 fixedly secured to base 11 having the uprights 12 supporting the table 13 which forms a cross member connecting with the uprights. 50

The platform 14 carrying the container or receptacle 15 is supported by the rod 16 mounted for vertical movement by the spaced scale beams 17 which are in turn rotatably carried from an upright 12. Members 18 suitably secured to the 55

upright are provided with ball bearing races 20, Figure 13, having associated therewith the projecting stud 21 which is rotatably mounted and to which the beam members 17 are secured by the nuts 22. The rod 16 is suitably secured to the yokes 23 which carry at their respective ends 24 and 25 the ball bearing races 26, the inner race member being secured in each instance to a transverse shaft 27 joining and fastened by 10 nuts 28 with the ends of the beam members 17. Vertical rods 30 also pivotally connect as at 31 with the scale beams and carry at their upper end the stud 32 associated with the trip mechanism which will be presently described. Projecting from the rear of each beam member 17 is a rod 33 suitably secured to the member by a securing nut 34, Figure 13, and which carries weight 35 adjustable along the length of the rod to vary the effectiveness of the weight in 15 counter-balancing the structure at the opposite end of the beam members including the vertical rod 16, platform 14 and container supported thereon. Movement of the weights outwardly will offer greater resistance to the downward movement of the platform and will pack the material into the container under a greater pressure. Also adjustment of the weights will adapt the scale beam to a variety of materials having different weights.

20 The ball bearing mounting of the beam members and the bearings rotatably connecting the vertical rod 16 with the members makes a substantially frictionless support for the platform and which is therefore very sensitive, giving 25 accurate performance during the weighing operation. Also the use of bearings provides strong, durable joints having long life and which do not collect dust and dirt as the design of mounting for the bearing race in all instances, 30 as shown in Figure 13, protects the moving parts.

The container or receptacle is supplied with material from the hopper 36 having a discharge spout 37 and communicating at its upper end with a conduit 38 which delivers the material to the hopper. As clearly shown in Figure 2 the fastening means 40 are formed integral with the hopper and serve to securely fasten the hopper to the upper end of the support 10. The discharge spout has a diameter considerably smaller 45 than that of the container so that the same will enter the container when empty, as shown in Figure 1.

The material in the hopper is fed from the discharge spout 37 by means of a feeding auger 41 in the form of an elongated screw detachably secured to the chuck 42 formed on the end of the drive shaft 43. The upper end of the auger is recessed at 44, Figure 6, and the chuck is provided with spring pressed balls 45 retained with 50 in openings 46 and forced inwardly into engagement with the recesses by the coil springs 47. The threaded nuts 48 hold the springs in the openings and serve to adjust their tension. This provides a firm and secure connection for the 55 auger and which permits ready and easy attachment and removal. Revolving around the feeding auger is an agitating member 50 which keeps the material within the hopper agitated and in a loose and free flowing condition for the feeding 60 auger. Member 50 is provided with a central boss 51 which is apertured for securing the member to the depending end of the tubular shaft 52 surrounding the drive shaft 43 and having rotation independently thereof. The elongated 65 bearing 53 depending within the hopper and

integral with the gear housing 54 provides the journalling means for the tubular shaft 52 and drive 43. An oil seal 55 seals the end of the bearing against the entrance of material and retains a lubricating medium within the bearing to insure efficient operation of the rotating members.

The electric motor 56 supported on bracket 57 supplies the source of power for rotating the feeding auger and agitating member. The pulley 58 secured to the operating shaft 60 of the motor is connected through belt 61 with pulley 62 on shaft 63 journalled in bearing 64 of the gear housing 54. Shaft 63 through the medium of the clutch 65 and clutch collar 66 drives the shaft 67 mounted for rotation in bearing 68 of the gear housing and which shaft has secured at its end the bevel gear 70. The drive shaft 43 for the feeding auger extends vertically through the gear housing 54 having its upper end journalled in bearing 71 thereof. Suitably secured to the 20 drive shaft is a bevel gear 72 having meshing engagement with gear 70 and which is accordingly driven by the electric motor 56. Pinion 73 having rotation with the bevel gear 72 meshes with gear 74 mounted within the gear housing 25 by the stud 75. Also mounted on stud 75 and rotated by gear 74 is a pinion 76 which in turn meshes with gear 77 secured to the tubular drive shaft 52. With the clutch operatively positioned to connect the electric motor with shaft 67 to cause rotation of gear 70 it will be understood that bevel gear 72 is accordingly driven and causes rotation of the feeding screw 41 to deliver the material from the hopper. The drive is transmitted from pinion 73, gear 74, pinion 76 30 and gear 77 to the tubular drive shaft 52, causing rotation of the member 50 and agitation of the material surrounding the feeding auger.

The collar 66 of the clutch is actuated by yoke 78 secured to shaft 80 journalled in the gear housing 54 and which shaft has secured to the ends projecting outside of the housing, Figures 1 and 3, levers 81 and 82, respectively. Lever 82 connects with coil spring 83 secured at its opposite end to support 84 and which serves to yieldingly 45 force the clutch collar into released position to thus maintain the constantly rotating shaft 63 disconnected from shaft 67. Lever 81 connects through the turnbuckle 85 with the pivoted arm 86 connecting with the plunger 87 of the electro-magnet 88 which is securely fastened to the platform 84. Energization of the electro-magnet functions to cause upward movement of the plunger 87 and thus actuation of the connecting links to cause rotation of shaft 80 in a direction 55 to operatively connect the clutch collar and clutch. A drive is therefore established from the electric motor to the pinion 70 which will rotate the feeding screw and agitating member as described.

Means in the form of trip mechanism is provided for actuating the electric switch to energize the electro-magnet and throw the clutch into engagement when the platform is raised and for holding the parts in operative position during descending movement of the platform until the 60 same reaches a predetermined point in its descent when the clutch elements are automatically disengaged. This mechanism shown in Figures 4 and 5 consists of a frame 90 secured to the support 10 and providing spaced members forming a 65 yoke from which depends the diagonal members 91. The frame pivotally supports a pair of spaced fingers 92 for location over the container or receptacle 15 and which are adapted to contact the container when the same is empty 70 75

and the platform is raised to cause resetting of the trip mechanism. The spaced fingers are suitably secured to the spaced transverse rods 93, one of which is provided with a plurality of nuts 94 having a knurled periphery to provide means which can be grasped by the operator in lifting or lowering the fingers as may be desired. Carried by the spaced rods 93 centrally thereof between the finger 92 is a metal block 95 which can be adjustably secured to the vertical supporting rod 96 pivotally carried by the arms 97 and 98. The lower arm 97 pivotally secured at its outer end to the supporting rod 96 has its end pivoted to the frame as at 100. The upper arm 98 is also pivoted to the frame by the stud 101 and extends a considerable distance to the side of said pivot opposite the fingers. The same includes a curved portion 99 terminating over a toggle joint to be presently described. This terminating end 10 carries a resetting screw 102 held to the arm 98 in proper adjusted position by the lock nut 103. The rearwardly extending portion of the arm also carries a weight 104 adjustable along the length of said portion and held in adjusted position by the set screw 105.

At the end of the members forming the yoke of the frame 90 are located pivot pins 106 having their pointed ends directed inwardly of the yoke for rotatably mounting the shaft 107, having secured thereto member 108 providing a vertical support 109 which carries at its upper end the mercury switch 110. Also secured to shaft 107 is a lever 111 connecting with lever 112 which in turn is pivoted to lever 113 projecting from the shaft 114 and forming the toggle joint, the center connection of which is located directly under the resetting screw 102. Pivot pins 115 project inwardly from the yoke on frame 90 and rotatably mount the shaft 114. Also fastened to shaft 107 is an arm 116 connecting with link 117 to which is secured one end of a coil spring 118 having its other end fastened at 119 to the diagonal member 91. The coil spring yieldingly forces arm 116 to the right, Figure 5, which tends to rotate shaft 107 counter-clockwise. When such rotation of shaft 107 is allowed to take place the support 109 for the mercury switch 110 is tilted in a direction toward the left, Figure 5, changing the angularity of the switch and causing the globule of mercury 50 in said switch to locate itself in the opposite end where electrical connection between the terminals 120 and 121 is terminated. The function of the toggle joint comprising the link 112 and lever 113 is to prevent rotation of the shaft 107 in a counter-clockwise direction and which can take place only by breaking the toggle joint and movement of the members upwardly, it being understood that for the purpose of the invention the members are so arranged that the toggle joint breaks with the 55 members moving upwardly. The toggle joint is also held in set position with the members horizontally aligned by the normally latched lever 122 formed integral with shaft 114 and projecting to the right thereof for contact with a shoulder 60 formed on member 123 having a companion or trip member 124 and which are integral with shaft 125. The shaft is pivotally mounted within frame 90 by the pivot pins 126. The stop screw 127 located centrally of the yoke provided by the frame 65 90 and retained in adjusted position by lock nut 128 is positioned for engagement with the upper end of member 123 to limit movement of said member toward the lever 122. Member 124 has a length to over-balance member 123 and hold the 70 same in contact with the stop screw. As more

clearly shown in Figure 1 the trip 130 carried by stud 32 is positioned for engagement with the end of the member 124 to cause upward movement of the member as the stud moves upwardly due to the downward descent of the platform. Upward 5 movement of member 124 will result in movement of member 123 away from its stop and will thus release the lever 122 to free the toggle joint, whereby actuation of the switch will take place to open the circuit to the electro-magnet 88 as 10 the shaft 107 carrying the switch is yieldingly biased by the coil spring 118.

As shown in Figure 3 the terminals 120 and 121 connect with a source of power and with the electro-magnet 88, respectively, the other side of 15 the source of power being also connected to a terminal of the electro-magnet by conductor 131. With the switch positioned as shown in Figure 5 it will be observed that the globule of mercury 20 is in contact with the terminals and that therefore the circuit to the electro-magnet is closed and the same is energized. The clutch has established the drive from the electric motor 56 to the feeding auger and agitating member and feeding of the material results. The positioning 25 of the switch to close the circuit to the electro-magnet has resulted from the placing of an empty container on the platform 14 and upward movement of the container to contact the fingers 92, 30 causing actuation of arm 98 and movement of the resetting screw 102 downwardly to straighten the toggle connection. The members of the toggle joint are held in said aligned relation by the lever 122 which has been caused to engage 35 the shoulder on member 123, thus holding the mechanism in latched relation.

The actuation of the mercury switch to close the electric circuit initiates the feeding of the material to the empty container and the same 40 continues with the container and platform gradually descending due to the added weight on the platform side of the scale beam. The descending movement of the platform results in upward movement of stud 32 and trip 130 carried thereby, 45 whereupon after a predetermined downward movement of the platform the trip is caused to contact member 124 and cause release of the lever 122. As the fingers 92 are free, the container having moved down out of engagement 50 with the fingers, the toggle joint is likewise free and breaking takes place upon the release of the lever 122. This results in rotation of shaft 107, and actuation of the mercury switch to separate the terminals and open the circuit to the electro-magnet. The coil spring 83 actuates the clutch collar to disengaged position immediately upon deenergization of the electro-magnet and as the drive to the feeding auger is thus intercepted the 55 feeding of the material stops.

Following the above sequence of operation the operator removes the filled container and replaces an empty container on the platform which is immediately forced upwardly to where the same 60 contacts the fingers 92 moving the resetting screw 102 downwardly to reset the trip mechanism.

In Figure 7 the fingers and associated structure which resets the trip mechanism is eliminated and modified resetting means substituted 70 therefor. To the upper end of stud 32 is secured an arm 132 carrying the resetting screw 133 locked in adjusted position by the wing nut 134. The arm locates the resetting screw directly over the center connection of the toggle 75

joint and the return of the toggle joint to aligned position to latch the mechanism is accomplished by said screw upon downward movement of the stud 32. This downward movement takes place 5 when corresponding upward movement of the platform is effected by the placing of an empty container on the same.

The invention also contemplates feeding means 10 for delivering material from the hopper wherein a plurality of feeding augers are operated for supplying the bulk of the material to the container and thereafter an auxiliary auger is operated to supply a dribble or secondary stream of 15 material to gradually bring the material in the container to the desired weight. The modified feeding structure shown in Figures 8, 9 and 10 comprises a hopper 136 having a discharge spout 137 provided with a plurality of openings 138 within which are located the main feeding augers 139 and a central opening 140 receiving the secondary or auxiliary feeding auger 141. This auxiliary auger is secured at 142 to the driving shaft 143 which extends through the gear casing 20 25 30 35 40 45 50 55 60 65 70 75 144 and projects above said casing, there being secured to the projecting end the pulley 145. Positioned on a second support 10 is a gear casing 146, the same journalling the vertical shaft 147 mounted in suitable bearings integral with the gear casing and projecting above the casing where the same has secured thereto the pulley 148 which operatively connects with pulley 145 through the belt 150. Shaft 147 has suitably secured thereto a bevel gear 72 identical with the bevel gear having the same numeral and located within the gear housing 54 in the structure of Figure 1. Said gear also has meshing engagement with a pinion 70 on shaft 67 which is rotated through clutch mechanism and other intermediate instrumentalities from an electric motor 56 as described. The auxiliary feeding auger is therefore driven from the motor supported on the companion support located to the side of the hopper 136, the driving shafts being operatively connected through pulleys 145, 148 and belt 150.

The main feeding augers 139 are detachably secured as at 151 to driving shafts 152 which are suitably journalled in the bearing 153. Each of the shafts 152 has secured thereto gears 154, Figure 9, which mesh with a central gear 155 secured to the tubular drive shaft 157 mounted in bearing 158 and surrounding and having rotation independently of shaft 143. Suitably secured to the tubular driving shaft is a bevel gear 72 which meshes and is rotated by pinion 70 driven through clutch structure and other instrumentalities identical to that shown in Figure 1.

Figure 11 shows the location on support 10 of 60 duplicate trip mechanism operatively connecting with spaced fingers 92 overlying and having engagement with the empty container 15 suitably supported by platform 14 under the discharge spout 137. Each trip mechanism is similar in construction and in operation to that shown in Figures 4 and 5, as previously described. However, for the purposes of the invention it is to be understood that the lower trip mechanism identified in its entirety by 160 has its mercury 65 switch electrically connected in circuit with the electromagnet associated with gear casing 144, journalling the tubular drive shaft 157 for rotating the main feeding augers 139, and that the upper trip mechanism designated in its entirety by 161, Figure 11, has its mercury switch

electrically connected in circuit with the electro-magnet associated with gear casing 146 journaling the shaft 147 providing the driving means for the auxiliary feeding screw 141. The trip arms 162 and 163 are secured in spaced relation 5 on stud 32 and associated with the trip member 124 of the mechanisms, respectively, being positioned to trip the mechanisms in sequence, arm 162 first actuating the lower trip mechanism to actuate the mercury switch thereof to open the 10 circuit and disconnect the drive to the main feeding augers 139. However, the auxiliary feeder continues in operation to gradually bring the material in the container to the proper weight. The continued upward movement of the stud 32 15 finally brings the arm 163 into contact with the trip member of the upper mechanism 161, opening the circuit and disconnecting the drive to the auxiliary feeder. It will be appreciated that by proper spacing of the trip arms 162 and 163 the 20 time interval between the stopping of the main feeding augers and the auxiliary auger can be varied to suit conditions and materials of different characteristics.

The scale beam of Figure 12 is modified by the 25 elimination of the vertical rods 30 located on the respective sides of the beam members 17 and the substitution therefor of a single upright 165 located centrally of the spaced beam members 17. Said upright has ball bearing connection 30 with said members through structure similar to that employed in connecting the vertical rod 16 as shown in Figures 1 and 13. This refinement in the construction of the scale beam provides frictionless bearings throughout and makes for a 35 more sensitive balance. The upright 165 carries the weight 166 which has been selected for the particular material being operated upon. The upright also carries trip arms 130 and 132 which function to trip and reset the trip mechanism 40 similar to the structure shown and described in Figure 7.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In a device of the character described, the combination with a vertically movable platform for supporting a container, of a hopper having a discharge spout positioned over the platform and adapted to be located within the container, means for feeding material from the hopper to cause downward movement of the platform and container as the same fills, an electric motor for operating said feeding means, connections between the motor and feeding means including a clutch resiliently held in inoperative position, electro-magnetic means for actuating and holding the clutch in operative position, and means including a latched lever adapted to be released by downward movement of the platform to open the circuit to the electro-magnetic means.

2. In a device of the character described, the combination with a vertically movable platform for supporting a container, of a hopper having a discharge spout positioned over the platform and adapted to be located within the container, means for feeding material from the hopper to cause downward movement of the platform and container as the same fills, an electric motor for operating said feeding means, connections be-

5 tween the motor and feeding means including a clutch, a resilient member biasing the said clutch into inoperative position, an electro-magnet, connections from said magnet to the clutch constructed and arranged to actuate the clutch and hold the same in operative position when the electro-magnet is energized, and trip means including a latched lever adapted to be released by downward movement of the platform to cause deenergization of the electro-magnet.

10 3. In a device of the character described, the combination with a vertically movable platform for supporting a container, of a hopper having a discharge spout positioned over the platform and adapted to be located within the container, means for feeding material from the hopper to cause downward movement of the platform and container as the same fills, an electric motor for operating said feeding means, connections between the motor and feeding means including a clutch, a resilient member biasing the said clutch into inoperative position, an electro-magnet, connections from said magnet to the clutch constructed and arranged to actuate the clutch and hold the same in operative position when the electro-magnet is energized, trip means including a latched lever adapted to be released by downward movement of the platform to cause deenergization of the electro-magnet, and means actuated by upward movement of the platform adapted to reset the trip means and energize said magnet.

15 4. In a device of the character described, the combination with a vertically movable platform for supporting a container, of a hopper having a discharge spout positioned over the platform and adapted to be located within the container, means for feeding material from the hopper to cause downward movement of the platform and container as the same fills, an electric motor for operating said feeding means, connections between the motor and feeding means including a clutch, a resilient member biasing the said clutch into inoperative position, an electro-magnet, connections from said magnet to the clutch constructed and arranged to actuate the clutch and hold the same in operative position when the electro-magnet is energized, trip means including a toggle mechanism adapted to be tripped by the downward movement of the platform to deenergize the electro-magnet, and members engaged by an empty container upon upward movement thereof to cause resetting of the trip means and energization of the electro-magnet.

20 5. In a machine for filling containers, the combination with a vertically movable platform for supporting the container, of a hopper having a discharge spout positioned over the platform and adapted to be located within the container, a plurality of feeding augers for delivering material from the hopper to cause downward movement of the platform and container, said augers being initially started simultaneously and operating in unison to feed the bulk of the material, and trip mechanisms actuated in sequence by the downward movement of the platform to stop the operation of certain of said feeding augers and then the remaining augers.

25 6. In a machine for filling containers, the combination with a vertically movable platform for supporting the container, of a hopper having a discharge spout positioned over the platform and adapted to be located within the container, a plurality of feeding augers operating within the hopper for delivering material to the container,

certain of said augers operating to feed the bulk of the material, and other of said augers feeding an auxiliary stream, and trip mechanisms actuated in sequence by the downward movement of the platform to stop the operation of said first mentioned augers, and after a predetermined interval of time to stop the operation of the auxiliary feeding augers.

7. In a machine for filling containers, the combination with a vertically movable platform for supporting a container, of a hopper having a discharge spout positioned over the platform and adapted to be located within the container, means for feeding material from the hopper to cause downward movement of the platform and container as the same fills, an electric motor for operating said feeding means, connections between the motor and feeding means including a clutch, electro-magnetic means actuating and holding the clutch in operative position when energized, and trip means including toggle mechanism adapted to be tripped by downward movement of the platform, said trip means operating a mercury vacuum tube switch to cause deenergization of the electro-magnetic means.

10 8. In a device of the character described, the combination with a vertically movable platform for supporting a container, of a hopper with a discharge spout positioned over the platform, and adapted to be located within the container, means for feeding material from the hopper to cause downward movement of the platform and container as the same fills, an electric motor for operating said feeding means, connections between the motor and feeding means including a clutch, a resilient member biasing the said clutch into inoperative position, an electro-magnet, connections from said magnet to the clutch constructed and arranged to actuate the clutch and hold the same in operative position when the electro-magnet is energized, trip means including a latched lever adapted to be released by the downward movement of the platform to deenergize the electro-magnet, and members adapted to be engaged by hand to cause resetting of the trip means and energization of the electro-magnet.

15 9. In a machine for filling containers, the combination with a movable platform for supporting the container, of a hopper having a discharge spout positioned over the platform and adapted to be located within the container, a drive shaft rotatably mounted within the hopper, a feeding auger fixed to said drive shaft and being centrally disposed with respect to the discharge spout, a tubular drive shaft also rotatably mounted within the hopper and concentrically disposed with respect to the first mentioned drive shaft, and a plurality of feeding augers rotated by said tubular drive shaft, said last mentioned augers being radially disposed with respect to the center auger and having operation to feed the bulk of the material to the container.

20 10. In a machine for filling containers, the combination with a movable platform supporting the container, of a hopper having a discharge spout positioned over the platform and adapted to be located within the container, a tubular drive shaft rotatably mounted within the hopper, means for rotating said tubular drive shaft, a plurality of feeding augers supported within the hopper and positioned within the discharge spout thereof, means operatively connecting each of said feeding augers with the tubular drive shaft whereby they have rotation to feed the bulk of the material

to the container, a drive shaft extending through said tubular shaft, independent means for driving said last mentioned drive shaft, and a feeding auger fixed to said center drive shaft and disposed centrally with respect to the first mentioned augers, said centrally disposed feeding auger having operation to deliver a secondary stream to the container.

11. In a machine for filling containers, the combination with a movable platform for supporting the container, of a hopper having a discharge spout positioned over the platform and adapted to be located within the container, means within the hopper for feeding material to the container, electric means for controlling the op-

eration of said feeding means, trip mechanism for opening the circuit to said electric control means, beam members pivotally supporting an upright at one end thereof having the platform secured thereto, a support for the beam members including bearings substantially frictionless mounting the beam members for oscillation, a second upright pivotally carried by said beam members at the opposite end thereof, means fixed to said second upright adapted to actuate said trip mechanism upon upward movement of the same, and other means fixed to said upright for resetting the trip mechanism upon downward movement thereof. 5 10

WARREN D. JORDAN. 15
